NO MODEL.

3 SHEETS—SHEET 3.

A detailed technical drawing of a mechanical assembly, likely a gear train, shown in a cross-sectional view. The drawing features several gears of different sizes and patterns, some with internal features like holes or notches. Various parts are labeled with numbers: 1, 2, 3, 4, 5, 6, 7, 8, 9, 10, 11, 12, 13, 14, 15, 16, 17, 18, 19, 20, 21, 22, and 23. The assembly includes a central vertical shaft with a gear, a horizontal gear train, and a side component labeled 14, 15, and 23. The drawing uses fine lines and cross-hatching to indicate different materials and assembly details.

UNITED STATES PATENT OFFICE.

ULYSSES S. KING, OF CHEROKEE, KANSAS.

MOTOR.

SPECIFICATION forming part of Letters Patent No. 733,217, dated July 7, 1903.

Application filed October 21, 1902. Serial No. 128,166. (No model.)

To all whom it may concern:

Be it known that I, ULYSSES S. KING, a citizen of the United States, residing at Cherokee, in the county of Crawford and State of Kansas, have invented new and useful Improvements in Motors, of which the following is a specification.

This invention relates to a motor for use exclusively underground in mines and the like; and one purpose of the same is to provide a compact and efficient device of this class which can be easily controlled and capable of drawing a heavy load.

A further purpose of the improvement is to so shape the motor that it will not interfere with mine-lead structures and will easily pass through the latter without requiring a change in the usual arrangement in contradistinction to motors having a cumbersome construction and obstructive lateral or other projections.

A further purpose of the improvement is to introduce in a device of this class a form of drive-gearing for the axles which will obviate any tendency to lost motion and capable of reversing to drive the motor in either direction, the gear being of such nature and the entire motor having such weight as to cause the latter to remain in tractive conjunction with rails, the said gearing positively actuating the motor through the operation of the driving medium embodied therein.

A still further purpose of the invention is to equip an underground motor with such detail accessories as to render it convenient in operation, strong and durable, and comparatively inexpensive in the cost of manufacture.

The invention consists in the construction and arrangement of the several parts, which will be more fully hereinafter described and claimed.

In the drawings, Figure 1 is a side elevation of an underground motor embodying the features of the invention. Fig. 2 is a top plan view of the same. Fig. 3 is a horizontal section taken in a plane below the engine or driving medium proper and showing parts of the clutch mechanism broken away. Fig. 4 is an end elevation of the motor. Fig. 5 is a longitudinal vertical section. Fig. 6 is a transverse vertical section on the line 6-6, Fig. 3. Fig. 7 is a longitudinal vertical section on the line 7-7, Fig. 3.

Similar numerals of reference are employed to indicate corresponding parts in the several views.

The numeral 1 designates a truck-frame comprising side and end bars or beams securely bolted or otherwise fastened together. In the complete organization of this frame it will be provided with bumpers or buffers and coupling means whereby either end of the motor may be attached to the cars. The side bars of the frame will also be supplied with suitable bearings or journal-boxes 2, in which the terminal journals or axles 3 are rotatably mounted, the said axles having flanged wheels 4 thereon of the usual construction to engage track-rails. In the frame 1 is a basket 5, which depends approximately on a level with the lower edges of the side and end bars or beams of the said frame and is bolted at its upper portion to lugs or projections on the side bars or beams, the latter having portions thereof projected at a greater elevation than the level of the upper edges of the end bars. This precise form of the frame is not essential, however, and may be varied at will to meet certain changes in construction of the motor that may be demanded to accommodate certain contingencies. The frame and the motor-journal, however, will be of such structure as to adapt it for general underground use without modification, except possibly in the proportions and minor detail accessories. The journal-boxes 2 are disposed in vertical slots 6 in the side bars or beams of the frame, and between the upper edges of the said boxes and outwardly-projecting caps 7 cushion-springs 8 are interposed, as in the usual car structures. On the axles 3 are spur-gears 9, meshing with an intermediate idler spur-gear 10, journaled on a stub-shaft 11, extending inwardly from one of the side bars or beams of the frame 1, as clearly shown by Fig. 3. The gears 9 and idler-gear 10 are held in continual mesh, and also meshing with one of the gears 9 is a motion-transferring pinion 12, journaled on a stub-shaft 13, also extending inwardly from one side beam of the frame 1 and of itself maintained in continual mesh with a drive-pinion 14 on a counter-shaft 15, having bearing at opposite ends in the side beams of the frame adjacent to one end of the motor. On the counter-

shaft 15 are clutch devices 16, including bevel-gears 17, so disposed as to operate the counter-shaft in opposite directions to control a reversal of movement of the motor and which 5 will be more fully hereinafter explained in detail.

Suitably disposed on the upper portion of the basket 5 is a gasoline-motor of a three-cylinder type, the several cylinders of this 10 engine concentrating their driving force on a single driving-shaft 18. The advantage of the three-cylinder type of gasoline-engine, which will not be herein specifically described, is an increased explosive force with a more 15 positive actuation and regularity in the rotation or operation of the driving-shaft 18, the latter having on opposite ends balance-wheels 19 for obvious purposes and at one end provided with a bevel-pinion 20 in such position 20 between the bevel-gears 17 on the counter-shaft 15 that either of the said gears may be quickly thrown into engagement with or adjusted in inoperative relation to the said bevel-pinion 20. Many forms of clutch 25 devices may be used to arrive at the results sought; but it is obvious that means must be provided for positively actuating said friction devices or clutch mechanisms to quickly and positively control the direction of movement 30 of the motor. One of the preferred forms of operating devices for shifting the clutch devices comprises a rock lever or rod 21, journaled or applied to the under part of the frame 1, to one side of the center, as clearly 35 shown by Fig. 3, and having an operating-lever 22 attached thereto and extending upwardly through the frame within convenient reaching distance of the engineer or motorman. Rising from one extremity of the 40 rock lever or rod 21 is an angular shifting-arm 23, having its upper end projected inwardly over the frame, at one extremity of the latter, and attached to a slide-bar 24, mounted in suitable bearings or boxes 25 at one end of 45 the frame, or that adjacent to the counter-shaft 15. The slide-rod 24 is disposed in a plane at right angles to the rock lever or rod 21 and has inwardly-extending shifting-arms 26 secured thereto and embracing circumferentially - grooved ends of clutch - sleeves 27, 50 slidable on the counter-shaft 15 and engaging a spline 28, projecting from the shaft, to rotate with the latter.

The gears 17 have outer tubular bodies 29 55 or contact members, with which expansible clutch members 30 are adapted to engage, and each comprises a hub 31, engaging the spline 28 adjacent thereto and having a clutch-rim 32 of such normal diameter as to fit within 60 the tubular body or contact member 29 of each gear 17. It will be understood that the gear 17 and its tubular body or contact member 29 in each instance is loose on the counter-shaft, and when the rim 32 co-operating therewith is in normal condition the shaft 15 will not be affected by either gear so far as 65 rotation is concerned until the rim 32 is ex-

panded to create a frictional bind thereof against the inner surface of the tubular body or contact member 29. The spline 28 which 70 is used in connection with each clutch device is long enough to compensate for longitudinal adjustment of each clutch device on the shaft 15 through the medium of the arms 26 and the devices controlling the latter. On the hub 75 31 of each rim 32, at a point diametrically opposite and above the spline 28 of the shaft 15, an expanding-lever 33 is pivotally secured and extends outwardly and upwardly and is movably attached by means of an upper joint 80 34 through the upper terminal of the screw 35 and a buckle 36, which includes a central nut 37, the lower terminal of the screw 35 being secured by means of a knuckle-joint 38 in a recess at the inner extremity of the upper part 85 of the sleeve 37. The expanding-lever, adjacent to its pivotal point on the hub 31, has a fulcrum-block 39 mounted therein, each expanding-lever consisting of two members, as clearly shown by Fig. 7, and the fulcrum-block provided with opposite trunnions 40 to engage said members. Adjustably rising from the fulcrum-block 39 is a screw post or shank 41, having a wedge-block 42 secured on the upper end thereof, with a guide-pin 43 rising vertically from the center thereof. The wedge-block 42 is held in line and partial engagement with the spaced terminals of the rim 32, and said block is adapted to be forcefully pushed upwardly between the ends of the 90 rim to expand the latter and create a frictional bind between the outer surface of the said rim and the inner surface of the tubular body or contact member 29 of the gear 17. To insure a reliable and positive operation of the wedge-block at all times in relation to the spaced ends of the rim 32, the guide-pin 43 is employed and moves in semicircular grooves 44 at the centers of the said spaced ends of the rim. In the primary adjustment of the parts 95 100 of each clutch device the wedge-block 42 is raised high enough to always occupy an operative position in relation to the spaced ends of the rim 32 through the medium of the screw post or shank 41, and through the use of the 105 fulcrum-block 39 the wedge-block throughout its full length is caused to fully engage the spaced ends of the rim irrespective of the angular position of the expanding-lever with 110 relation to the hub 31. It is obvious that 115 more or less wear will ensue on the rim 32 in consequence of continued use, and if nothing were provided to compensate for such wear the positive operation of each clutch device would soon become impaired, but through 120 the medium of the turnbuckle 36 the expanding-lever 33 can be easily adjusted when necessary to compensate for wear on the rim, and thereby always insure a positive engagement 125 of said rim with the inner surface of the tubular body or contact member 29 of the gear 17. It will be understood that each clutch device is duplicate in construction, and the 130 shaft 15 has two splines 28, so that the actu-

ation of the shaft by the individual clutch devices may be independent. When the slide-bar 24 is shifted in opposite directions to operate either one of the clutch devices in accordance with the direction it is desired the motor shall move, the clutch device shifted on the shaft will be thrown into engagement with the pinion 20 on the shaft 18 through the medium of the gear 17 of said clutch device, and when the sleeve 27 is shifted and mesh of the operated gear 17 with the bevel-pinion 20 is obtained the resistance to further movement of the said clutch device will cause the expanding-lever 33 to be thrown outwardly and force the wedge-block 42 between the spaced ends of the rim 32, and thus transmit motion from the shaft 18 to the gear 20 and operated clutch device to the shaft 15 and from the latter through the drive-pinion 14 and motion-transmitting pinion 12 to the gears 9 on the axles 3, and thus propel the motor in a positive manner. The adjustment of the slide-bar 24 in either lateral direction will be maintained by suitable retaining devices arranged adjacent the lever 22, and it will be understood that many mechanisms for this purpose could be used. To insure a tight non-slipping engagement between the rim 32 and the inner surface of the tubular body or contact member 29, said gear is provided with a circumferential covering 45 of vulcanite fiber or other analogous material. It is required in mines and other underground tunnels or passages that a certain amount of fresh air be supplied to sustain human and animal life, and it is necessary in providing a motor for underground use to equip the same with means for preventing a devitalization or vitiation of the fresh air or in any wise contaminating the same with noxious odors or gases from the motor or to in the least diminish the quantity of air required. This supply of fresh air in mines particularly is governed by local laws and must be preserved. To meet this requirement, the present improved motor is equipped with a muffler 46, consisting of a cylinder containing water, as at 47, and extending from the engine is an exhaust-pipe 48, having a depending member 49 projecting into the muffler near the lower or bottom portion of the cylinder. The upper portion of the cylinder 46, at a point distant from the entrance thereto of the exhaust-pipe, is an outlet 50, as clearly shown by Fig. 2, and the gases or noxious odors are conveyed by the said pipe 48 from the engine to the muffler and absorbed by the water, and what steam that is in excess of the absorption or condensation, particularly after the water in the muffler becomes heated, escapes through the outlet 50 without carrying therewith any of the gases or odors from the engine due to the explosions, and thus contamination of or injury to the fresh-air supply within a mine lead or passage is prevented and the fresh-air supply remains unimpaired.

From the foregoing it will be perceived that the improved motor is constructed to meet the various contingencies and conditions existing in underground passages or mine-leads without requiring a modification or adaptation of the framing structure within said leads or passages. The gearing in connection with the axles is of a strong and durable nature, and the weight of the entire motor will be such that on a dry track or track-rails in view of certain resistance it will cause the wheels on the axles to slip on the rails with obvious advantages in motor or locomotive device constructions, as will be readily appreciated by those skilled in the art. Moreover, it is proposed to proportion the motor in such manner as to permit the use of a broader-gage track than is ordinarily employed in underground motors, with a resultant stability and greater efficiency in the movement of the motor, particularly in drawing heavy loads. The motor is also constructed with maximum strength in view, and it is intended to incorporate therein as a part of its organization motive mechanism of compact form with increased power having advantageous speed qualifications and which is derived from the employment of a triple-cylinder type of engine.

Having thus fully described the invention, what is claimed as new is—

1. In an underground motor, the combination of a frame having wheeled axles, gears on the axles, an intermediate idler-gear continually meshing with the gears on the axle, motive mechanism supported by the frame above the axle and including a shaft having a bevel-pinion on one end thereof, a counter-shaft having clutch devices thereon comprising bevel-pinions adapted to be thrown in and out of mesh with the pinion on the said shaft included in the motive mechanism, a drive-pinion carried by the counter-shaft, a power-transmitting pinion held in continual mesh with the drive-pinion and the gear on one of the axles, and means for shifting the clutch devices to change the direction of movement of the motor.

2. An underground motor shaped to move through constricted passages and comprising a frame mounted on wheeled axles, intermeshing gears on the axles and frame, a counter-shaft having a drive-pinion, a motion-transmitting pinion between the drive-pinion and one of the axle-gears, clutch devices on the counter-shaft, motive mechanism including a longitudinal shaft having a pinion on one end, clutch devices on the counter-shaft for engagement with the said pinion and including bevel-gears, and means for shifting the said clutch devices to change the direction of the motor.

3. In an underground motor, the combination of a frame, wheeled axles on which the frame is disposed, gears on the axles and a part of the frame held in continual mesh, motive mechanism including a longitudinal

- shaft located above the wheeled axle, the said shaft having a pinion on its one end, a counter-shaft having clutch devices to engage the said pinion and control the direction of movement of the motor, motion-transmitting devices between the counter-shaft and one of the axle-gears, and means for shifting the clutch devices on the counter-shaft to control the movement of the motor.
- 15 4. In an underground motor, the combination of a frame, wheeled axles on which the frame is disposed, gears on the axles and a part of the frame, a motive mechanism comprising triple cylinders, and a single motor-shaft on which the driving effect of the said cylinders is concentrated, the said shaft having a pinion at one end, a counter-shaft having clutch devices thereon for engagement with the said pinion, and transmitting gear devices interposed between the counter-shaft and the gear on one of the axles.
- 20 5. An underground motor comprising a

frame mounted on wheeled axles, intermeshing gears on the axles and a part of the frame, a counter-shaft having gear devices co-operating therewith and with one of the axle-gears, clutch devices on the counter-shaft, motor mechanism including a shaft having a pinion on one end to co-operate with the said clutch devices, a rock-lever movably mounted against the under part of the frame having an angular arm secured thereto, a transversely-extending side bar to which said arm is connected and having inwardly-projecting arms in operative connection with the clutch devices on the counter-shaft, and means for operating the said rock-lever.

In testimony whereof I affix my signature in presence of two witnesses.
